CLAIM

The ornamental design for a kitchen island unit, as shown and described.

DESCRIPTION

FIG. 1 is a perspective view of a kitchen island unit showing the design;

FIG. 2 is a front elevational view of the kitchen island unit of FIG. 1;

FIG. 3 is a rear elevational view of the kitchen island unit of FIG. 1;

FIG. 4 is a top plan view of the kitchen island unit of FIG. 1;

FIG. 5 is a bottom plan view of the kitchen island unit of FIG. 1;

FIG. 6 is a right elevational view of the kitchen island unit of FIG. 1;

FIG. 7 is a left elevational view of the kitchen island unit of FIG. 1; and,

FIG. 8 is another perspective view of the kitchen island unit of FIG. 1 with an exemplary configuration including a countertop, drawers, an appliance, and storage units.

The dash-dash broken lines in the drawings depict portions of the kitchen island unit that form no part of the claimed design. The long dash-dot broken lines in the drawings define the boundaries of the claim and form no part thereof.
